United States Patent Office.

WILLIAM YOUNG, OF EASTON, PENNSYLVANIA.

Letters Patent No. 66,438, dated July 2, 1867.

IMPROVEMENT IN STEAM-GENERATORS.

The Schedule referred to in these Letters Patent and making part of the same.

TO ALL WHOM IT MAY CONCERN:

Be it known that I, WILLIAM YOUNG, of Easton, in the county of Northampton, and State of Pennsylvania, have invented a new and useful Improvement in Steam-Generators; and I do hereby declare that the following is a full, clear, and exact description thereof, which will enable others skilled in the art to make and use the same, reference being had to the accompanying drawings forming part of this specification.

This improvement relates to a new portable arrangement and combination of parts for the purpose of generating steam for various purposes, and the invention consists in arranging a boiler or generator over a fire-box and connecting it with a steam-drum (which stands above it) by pipes; and also in a device for heating the water before it is pumped into the generator, as will be hereinafter more fully described.

Figure 1 represents an elevation of the generator, partly in section, showing the form of the fire-box and generator with the steam-drum attached, but with the water-heater removed.

Figure 2 is a vertical section of the whole apparatus through the line *x x* of fig. 1.

Figure 3 is a top view of the water-heater.

Figure 4 shows an outside view of the heater detached.

Similar letters of reference indicate like parts.

A represents the generator or water-leg; B is the furnace or fire-box. C is the steam-chamber or drum. C' is the steam-space. D represents the water-heater. E and F represent pipes connecting the generator with the steam-chamber. G is a central flue through which the products of combustion pass. H represents the grate; J is the ash-pit. K is a pipe through which the steam is discharged.

This steam-generator is a portable arrangement which is designed to be used for various purposes. Especially is it designed for use in the winter season for thawing out frozen water-wheels, frozen water pipes, &c., or for boiling water or vegetables in wooden vessels, and for a great variety of purposes. It will be seen that there is a large fire-surface in fire-box, and that the whole flue is steam-generating surface. The heater D is not permanently attached to either the water-leg or the steam-drum, and it can be dispensed with if desired, but it is convenient for supplying the generator with hot water, as it may be connected with the force-pump for that purpose. The water is made to occupy a portion of the steam-chamber, and the pipes E and F are so connected at their top and bottom ends that there is a circulation of water through them when steam is being generated. The central flue G is a continuation of the fire-box, and it is permanently attached to the steam-drum C, but is removable from the top of the fire-box by uncoupling the pipes E F. These pipes are united by screw-couplings, as seen at *m n*. *o* is a tube to which the force-pump pipe is attached, and which is provided with a check-valve. P is a try-cock. R is a cock in the heater from which the heated water is discharged. S is a projecting spout which receives the water to be heated. U is the door; and T is the door-way through which the fuel is introduced into the fire-box. This door-way is permanently attached to the flue G, and the parts of the water-heater marked *v* fit around it. These generators may be constructed of any suitable materials and may be made of any desired size.

What I claim as new, and desire to secure by Letters Patent, is—

I claim the water-heater D arranged with reference to the fire-box B, the flue G, and the steam-chamber C, for the purposes set forth.

WILLIAM YOUNG.
